HOLDER

Julius M. Kahn, Englewood, N. J., and Sidney Bernstein, Brooklyn, N. Y., assignors to David Kahn, Inc., North Bergen Township, N. J., a corporation of New Jersey

Application April 30, 1956, Serial No. 41,277

Term of patent 14 years

(Cl. D80—9)

Fig. 1 is a front elevational view of the display device showing our new design.

Fig. 2 is a top plan view;

Fig. 3 is a bottom plan view;

Fig. 4 is an elevational view looking from the right of Fig. 1;

Fig. 5 is a perspective view taken from a point above the display device, the latter having been rotated anti-clockwise approximately 135° from the position shown in Fig. 1.

We claim:

The ornamental design for a holder, substantially as shown and described.
